UNITED STATES PATENT OFFICE.

ERNEST H. BRANDT, OF CLERMONT, IOWA.

RATCHET MECHANISM FOR CEMENT-MIXERS.

1,125,052.

Specification of Letters Patent.

Patented Jan. 19, 1915.

Application filed October 26, 1912. Serial No. 727,973.

To all whom it may concern:

Be it known that I, ERNEST H. BRANDT, citizen of the United States, residing at Clermont, in the county of Fayette and State of Iowa, have invented certain new and useful Improvements in Ratchet Mechanism for Cement-Mixers, of which the following is a specification, reference being had therein to the accompanying drawing.

This invention relates to a ratchet mechanism and has special reference to a ratchet mechanism adapted to be used upon a portable mixer arranged to mix the cement as the same is being drawn from one place to another.

The principal object of the invention is to improve and simplify the general construction of devices of this character.

Another object of the invention is to provide an improved means for attaching the mixing box to a vehicle axle so that the box will be rotated by the rotation of said axle.

With these and other objects in view this invention consists in certain novel combinations, constructions, and arrangement of parts as will be hereinafter fully described and claimed.

In the accompanying drawings:—Figure 1 is a section taken transversely through the axle. Fig. 2 is a rear view of the machine. Fig. 3 is a view of a clutch device used herewith.

In the construction of this machine there is provided an axle 10 whereon are revolutionally mounted wheels 11, each of said wheels being provided with a hub 12 having a hollow chamber 13 formed therein. On the axle are collars 14 and on each end of the axle 10 there is provided a cap nut 15 and the hub 12 is so arranged as to slide between the collar 14 and this cap nut. Bearing on the inside of each collar is one end of a coil spring 16 the other end of which bears against the flange 17 formed within the hollow portion of the hub. This hub is provided on its inner face with a series of ratchet teeth 18 which engage ratchet teeth 19 formed on a clutch member 20. Supported on the clutch members 20 is a box or casing 21 provided with a hinged lid 22 and having the usual hasps 23. On each end of this casing is a pair of parallel strips 24 and extending through the axle and clutch member 20 is a bar 25 which lies between parallel strips 24 and serves to turn the receptacle when the device is drawn forward,

since the spring 16 holds the ratchet teeth 18 carried by the hub 12 in engagement with the ratchet teeth 19, carried by the clutch 20, as the spring 16 bears at one end upon the flange 17 and at the opposite end upon the collar 14. For the purpose of driving the device from place to place a draft frame 26 is secured to the cap nuts 15 and to this draft frame is attached a pole 27 carrying the double tree 28 to which is secured the swing trees 29 so that horses may be attached to the device.

In operation the receptacle is partially filled with a mixture of cement, sand, and broken stone or such other mixture as may be desired and this mixture is mixed to a suitable degree. The device is then placed in the place desired to deposit the material and as it moves along the box will be rotated with the result that the contents will be thoroughly mixed. By reason of the provision of the bar and parallel strips at each end there is no danger of the receptacle working loose on the axle as the leverage given the bars 25 at their outer end, as said bars extend for a considerable distance beyond said axle, is sufficient to prevent loosening of said receptacle. Before arrival at the place of deposit the vehicle is stopped with the box in an up-side-down position. If it is not in exactly the right place it may be backed in place as the ratchet mechanism will allow such movement without turning the box as the vehicle is backed, the lid may then be unlatched and the contents dumped where desired. There has thus been provided a simple and efficient device of the kind described and for the purpose specified.

Having thus described the invention what is claimed as new, is:—

A clutch of the class described comprising a primary and auxiliary section, a shaft supporting said sections, means for keying one of said sections through said shaft, the other of said sections being reciprocably mounted upon said shaft, a nut threaded upon the outer end of said shaft and provided with an overhanging flange portion fitting over one end of one section of said clutch for limiting the lateral movement of said last mentioned section upon said shaft, a collar carried by said shaft for limiting the inward movement of said last mentioned section upon said shaft, gripping teeth formed upon the respective sections of said clutch, said last mentioned section of said

clutch provided with an inwardly extending flange along its inner end, and a spiral spring engaging said collar on said shaft and said last mentioned flange for urging 5 an inward pressure upon said last mentioned section of said clutch.

In testimony whereof I hereunto affix my signature in presence of two witnesses.

ERNEST H. BRANDT.
